UNITED STATES PATENT OFFICE

ARTHUR BOOR, OF TOLEDO, OHIO, ASSIGNOR TO THE WILLYS-OVERLAND COMPANY,
OF TOLEDO, OHIO, A CORPORATION OF OHIO

CYLINDER HEAD

Application filed October 22, 1925. Serial No. 64,064.

This invention relates to internal combustion engines and more particularly to engines of the poppet valve type in which the cylinder head is removable.

5 One of the objects of the invention is to provide an engine with a removable cylinder head that is composed of a material having high heat conductivity characteristics.

Another object of the invention is to provide 10 a multi-cylinder engine with individual cylinder heads.

A further object of the invention is to provide a multi-cylinder engine with cylinder heads of a highly conductive material and 15 to provide for the increased expansion due to the use of such a material.

Other objects relating to details of construction and economies of manufacture, will appear from the description of the invention 20 to follow, certain embodiments of which, for the purposes of the present application, I have illustrated in the accompanying drawings, in which

Figure I is a transverse vertical cross section of an engine embodying one form of the invention.

Fig. II is a top plan of the cylinder block with the head removed, the view being taken substantially on the line 2—2, Fig. I.

30 Fig. III is a plan view of the engine cylinder portion showing the cover in position.

Fig. IV is a sectional view of the cover and cylinder head taken on line 4—4 of Fig. III.

Fig. V is a plan view of the cylinder head 35 used on the cylinder to the extreme left as shown in Fig. II.

Referring to the drawings in which like numerals refer to like parts throughout the several views, 1 represents a cylinder of an 40 internal combustion engine in which reciprocates piston 2 connected to crankshaft 3 by rod 4. Covering the upper end of cylinder 1 and valves 9 is a head 5 of a material having high heat conducting characteristics, such as 45 aluminum. Head 5 is secured to the main cylinder casting 6 by studs 7 and nuts 8 and is somewhat dome-shaped over valves 9 in order to allow the valves to clear the head when raised to their open position and also to 50 provide a clear passage to the cylinder 1.

A separate head 5 is provided for each of the engine cylinders, all heads being substantially alike except for the manner in which they are secured to the cylinder casting. The heads covering the end cylinders are provided at 55 one side with holes 10 through which project the studs 7 and at the other side with semi-circular notches 11 which align with similar notches on the mating side of the adjacent head and permit the contiguous sides of adjacent heads to be held with the same studs. 60 The heads for the intermediate cylinders, of a four cylinder engine such as illustrated will have semicircular notches on both sides of head 5 because each side of the head is adjacent a similar side of another head. Openings 65 12 are provided in head 5 which communicate with the cylinder surrounding space 13, by means of opening 14.

A suitable cover 15 is adapted to cover all 70 of the cylinders and is secured thereto by upward extensions of studs 7 and nuts 16, packing 17 being interposed between the head 5 and cylinder casting 6 to insure a tight joint. Each head 5 is provided with an upstanding 75 portion 18 which projects through an opening 19 in cover 15 and permits the insertion of ignition plug 20. Cover 15 is provided with a conical depression immediately surrounding head portion 18 for the reception of packing 80 ring 21 which is forced into contact with the head portion 18 and cover 15, by washer 22 and nut 23. Cover 15, except at opening 19, is spaced from cylinder 5 so as to provide a 85 space 24, for a suitable cooling medium, which is in communication with the cylinder jacket space 13. Outlet 25 serves to direct the cooling medium circulating in space 24 into a radiator (not shown) from whence it is returned to the engine jacket space 13, in the 90 usual manner.

Internal combustion engines, as usually constructed, are surrounded by similar spaces containing a cooling medium but as the head portion is subjected to the greater heat it is 95 desirable to construct the cylinder head of a material having high thermal conductivity and to construct the cylinder portion of a material, such as iron, having good wearing qualities and acting as an excellent bearing 100

material for the pistons to move upon. Cylinder heads formed of a highly conductive material enable the engine builder to obtain more power from a given size engine, as the compression may be materially increased. At 5 present, the compression is limited by fuel detonation which occurs in a hot engine after the compression exceeds a critical point which is usually around 65 to 70 pounds per square inch, but if the heat of the head be dissipated at a higher rate, the compression may 10 be raised beyond the previous critical point and the efficiency of the engine increased. Unfortunately the use of a metal having high 15 thermal conductivity introduces difficulties because of its relatively higher coefficient of expansion under heat. The difference in expansion during heating and cooling of a large engine produces considerable relative movement 20 between the contacting surfaces and results in destroying the desirable leak-proof contact between the head and cylinder. This is especially true of multi-cylinder engines in which the relative movement is increased proportionately to the length of the head that is 25 necessary to cover all of the cylinders.

The present invention eliminates the above mentioned troubles by securing each cylinder head to its cylinder as a separate unit and 30 then covering all of the heads with a single cover in order to provide a cooling chamber common to all cylinders with a single outlet. The individual cylinders of multi-cylinder engines are of small dimensions as compared 35 with the engine as a whole, and the movement of each head relative to the cylinder is correspondingly reduced. Holes and grooves 10 and 11 may be made slightly larger than studs 7 but it has been found that the ordinary 40 clearance given to holes of this character is quite sufficient and that if the holes are large enough to permit the free installation of head 5 onto cylinder casting 6 by sliding the head over studs 7, no trouble will be experienced. 45 The use of individual heads reduces the movement of each unit to an amount that does not destroy the joint between cylinder and cylinder head and the mating surfaces may be kept tight indefinitely, while the encompassing 50 cover permits of simple connections for the circulation of the cooling medium about the separate heads. I prefer to construct the heads as individual units, so as to receive the maximum benefit from the use of the invention, but in small engines or in those engines 55 wherein it is not considered necessary to obtain all possible value of the invention, two or more heads may be cast together, even though such procedure lessens the derived 60 benefit.

While I have shown and described, somewhat in detail, one embodiment of the invention, it is to be understood that this showing and description are illustrative only and that 65 I do not regard the invention as limited to the

details of construction illustrated and described herein, except in so far as I have included such limitations within the terms of the following claims, in which it is my intention to claim all novelty inherent in my invention, broadly as well as specifically. 70

I claim as my invention:

1. In a multi-cylinder poppet valve engine having inlet and exhaust valves arranged laterally of the cylinders, the combination of a separate head for each cylinder, said head forming a closure for the upper end of the cylinder and a passage from its individual valves to said cylinder, said head having all of its cylinder contacting surface in the same plane, and a cover extending over a plurality of said heads and spaced therefrom there being a clearance horizontally between said heads and said cover, said cover being supported by said cylinders and means for 80 securing said cover to said cylinders. 85

2. In a multi-cylinder poppet valve engine having inlet and exhaust valves arranged laterally of the cylinders, the combination of a separate cylinder head for each cylinder, said head forming a closure for the upper end of said cylinder and a passageway from its individual valves to the cylinder, said head and cylinder having their contacting surfaces in the same plane, a cover secured to said cylinders extending over a plurality of cylinder heads and spaced therefrom for confining a cooling medium, jackets surrounding said cylinders and spaced therefrom, and means permitting intercommunication between the head space and the cylinder space whereby the cooling medium is free to circulate around said cylinders and said heads. 95

3. In a multi-cylinder engine having inlet and exhaust valves arranged laterally of the cylinders, the combination of cylinders having surrounding cooling spaces, separate closures for the upper ends of said cylinders, said closures being formed of a material having greater heat conductivity than the cylinder material and forming a passageway from its individual valves to said cylinders, and a cover spaced from but enclosing a plurality of said heads and forming with the walls of said cylinders a compartment in communication with the cylinder cooling spaces. 105

4. In a multi-cylinder engine having inlet and exhaust valves arranged laterally of the cylinders, the combination of separate heads for the engine cylinders, each of said heads forming a passageway from its individual valves to its cylinder and formed of a material having greater heat conductivity than the cylinder material, a cover secured to said cylinders and inclosing a plurality of cylinder heads for directing a cooling medium about said heads, said cover having openings therein for allowing a portion of each of said heads to project therethrough and means for sealing said opening. 115 120 125 130

5. In a multi-cylinder engine having inlet and exhaust valves arranged laterally of the cylinders, the combination of cylinders having surrounding jacket spaces with openings at the upper ends, a separate head secured to each of the cylinders composed of a material having a different heat conductivity from the material of the cylinders, said heads covering the upper end of the cylinders and extending over the valves for providing a passageway to said cylinders, a cover secured to said cylinders and extending over a plurality of said heads for forming a cooling medium enclosure, and means on said heads whereby the openings in the cylinder jacket spaces may communicate with the enclosure between said cover and said heads.

10 6. In a multi-cylinder engine having inlet and exhaust valves arranged laterally of the cylinders, spaced individual cylinder heads forming closures for the upper ends of each of the cylinders, said heads providing individual passageways from said valves to said cylinders, said heads being formed of a material having a higher thermal conductivity and a higher coefficient of expansion than the cylinder material and said heads being constructed as units forming closures for a less number of cylinders than the total number 15 of cylinders included by the engine, and said heads being secured to said cylinders by means which permit slight relative motion.

20 7. In a multi-cylinder engine having inlet and exhaust valves arranged laterally of the cylinders, the combination of cylinder heads composed of a material having a higher thermal conductivity and a higher coefficient of expansion than the cylinder material, said heads forming closures for the upper ends of 25 the cylinders and individual passageways from the valves to the cylinders, said heads being constructed as units forming closures for a less number of cylinders than the total number 30 of cylinders included by the engine and a single cover secured to the cylinders and spaced from said heads for forming a compartment therewith.

35 In testimony whereof, I affix my signature.

40 50

ARTHUR BOOR.
